FIG. 1.

FIG. 2.

FIG. 3.

UNITED STATES PATENT OFFICE.

HARRY LICHTMAN, OF NEW YORK, N. Y., ASSIGNOR TO THE COPARTNERSHIP OF POWERS, FRIEND & LICHTMAN, OF NEW YORK, N. Y.

FURNITURE COVER.

Application filed January 8, 1926. Serial No. 80,106.

This invention relates to an ornamental form and more particularly to a table cloth, combining ornamentation and utility.

It has for its object the forming of a furniture cover with a pocket or receptacle in which the ornamental features of the cover and the pocket combine in a peculiar manner. A further object of the invention is the provision in a table cover of a receptacle to 10 contain a napkin or other article and ornamenting the receptacle and cover whereby a finished design is produced when the pocket is used or when it is empty. A still further object of the invention is the provision in a 15 card table cover of a series of napkin-holding pockets so arranged upon the cover and in relation to each other as to form no obstacle to the use of the cover in card playing and yet be useful when refreshments are served.

20 Other objects and advantages of the invention will hereinafter appear in the following description and the novel features thereof will be particularly pointed out in the appended claims.

25 In the drawings like reference characters indicate like parts throughout the several figures, in which Figure 1 is a plan of a table cover embodying my invention, Figure 2 is an opened napkin chosen to illustrate my invention, and Figure 3 is a sectional view through one of the pockets with folded napkin therein.

30 While a card table cover, rectangular in plan, provided with napkin-holding pockets, has been chosen to illustrate the invention, it will be appreciated that the inventive idea may be embodied in ornamental forms or other configurations, and that receptacles of somewhat different character could as well 35 have been chosen.

The table cover 10 is usually made of cloth which is sold as stamped goods ready to be worked with colored threads into a pleasing ornamental design, the pocket 11 to be 40 formed on the cover in any suitable manner. As shown, it is a separate piece or flap to be sewed or stitched to the body of the cover to the form of a basket body. The flap forms with the body of the cover a pocket in which a napkin 12 when properly folded 50 may be inserted.

The flap is suitably ornamented in simulation to the ornamented basket body. The design of the basket is completed by ornamenting that portion of the cover adjacent 55 the flap in the form of a basket handle. In the present instance, the ornamentation is carried further and the cover is embroidered in simulation of sprays of leaves and flowers, 13, 13', projecting from the basket; and the 60 corner 14 of the napkin 12 is ornamented with like sprays, 15, 15' whereby when the napkin is properly folded and inserted in the pocket, the embroidered ornamentation on the napkin will blend with that on the 65 cover to form a pleasing whole.

It will be observed that at the corner 16 of the cover has been shown a napkin in place while at the corner 17 the napkin has been omitted. In either case, however, the 70 ornamentation has been preserved.

75 While a cover with a single pocket as just described is within my contemplation of the invention a cover which is provided with a series of these pockets all projecting inwardly and spaced upon the cover in the manner shown offers particular advantages in an article of this kind. The center of such a cover is open so that the playing of cards is not interfered with. The space 80 immediately in front of a player is likewise unobstructed. At the same time, the pocket at the corner affords a suitable holder for a napkin which is to be used upon the serving of refreshments while at the same time 85 combining with the ornamentation of the cover in the production of a pleasing effect.

Having thus described my invention, what I claim as new and desire to secure by Letters Patent is:

90 1. An ornamental form adapted for sale as an entirety embodying an embroidered table cover, an embroidered pocket formed thereon in simulation of an object and a folded and embroidered napkin adapted to be 95 inserted in said pocket, the embroidery on the pocket and on the exposed portion on the napkin and on the contiguous portion of the cover forming a complete ornamental design, and the napkin being removable from the pocket without destruction of the said ornamental design.

- 5 2. An ornamental form adapted for sale as an entirety embodying an embroidered table cover, a pocket formed thereon, and a folded and ornamented napkin adapted to be inserted in said pocket, the ornamentation on the exposed portion of the napkin forming with the embroidery on the contiguous portion of the cover a complete ornamental design, and the napkin being removable from the pocket without destruction of said ornamental design. ¹⁰

¹⁵ In testimony whereof I affix my signature.

HARRY LICHTMAN.
